UNITED STATES PATENT OFFICE.

OTTO J. GROEHN, OF DETROIT, MICHIGAN, ASSIGNOR TO CLAYTON & LAMBERT MANUFACTURING COMPANY, OF DETROIT, MICHIGAN, A CORPORATION OF MICHIGAN.

BURNER CONSTRUCTION.

Application filed January 16, 1922. Serial No. 529,510.

To all whom it may concern:

Be it known that I, Otto J. GROEHN, a citizen of the United States of America, residing at Detroit, in the county of Wayne 5 and State of Michigan, have invented certain new and useful Improvements in Burner Construction, of which the following is a specification, reference being had therein to the accompanying drawings.

10 This invention relates to torch construction and refers more particularly to blow torches or the like although the invention in certain of its broader aspects is not limited to the particular type mentioned.

15 Among the objects of the invention are to provide a construction having better resistance to breakage or injury of the parts than those now in use, and one which can be economically manufactured. The invention 20 also resides in the novel arrangement of the burner wherein an integral supporting lug is used for not only strengthening the parts but also conducting the heat to the burner nozzle where great heat is desirable. Other 25 features of the invention reside in the novel supporting basis for the tank of the torch and in such other details of construction and arrangements and combinations of parts as will more fully hereinafter appear.

30 In the drawings:

Figure 1 is a side elevational view partly in section of a blow torch embodying my invention;

35 Figure 2 is a longitudinal elevation view in cross section of the burner, and

Figure 3 is a section along 3—3 of Figure 2.

40 Describing in detail the particular embodiment of my invention shown in the drawings, A designates the tank of the torch provided with the usual handle B and supporting standard C which carries the burner D. Fuel from the tank to the discharge nozzle X of the burner is controlled by a 45 valve E operated by the handle E' on the stem E² and the usual starting drip cup G is provided, the parts so far described being of the usual construction.

45 At its lower end the tank A is provided 50 with a base H which serves not only as a support for the tank and a guard for the lower end thereof but is also utilized for securing the bottom A' of the tank to the lower side wall A² thereof in a novel manner. As shown in detail in Fig. 1 the lower

end of the side wall A² is outwardly offset at J and terminates in a curved or rolled portion J' which receives the lower end A³ of the bottom A'. These parts are first constructed and assembled and secured together in assembled position, but the base H is also used as a securing member in the following manner. Near its upper end the base H has a downwardly offset portion H' which terminates in a roll H² extending 60 around the roll J' thus locking the base to the tank and also assisting in forming the joint between the bottom of the tank and the side walls thereof. A very important feature of this construction is the fact that it reduces the area at the bottom of the tank as compared with a bottom formed at the lower edge of the base H. In previous constructions difficulty has been encountered 65 owing to such bottoms blowing out on account of the great area and this objection is overcome in the present construction. Not only does the rolled in flange H² tend to reduce the area of the bottom of the tank but it also forms a reinforcement. This 70 novel construction has a further advantage 75 that it permits of the usual brass tank construction while providing a steel base for the same.

The burner D has the usual combustion chamber K into which fuel from the nozzle X is discharged. In structures of this type it is customary at the rear of the combustion chamber and at substantially the forward end of the discharge nozzle to provide air 80 ports such as the ports L. In the present construction these ports are provided by spaces left between the bottom portion M having a passage M' for conducting fuel to the nozzle X and the top lug N. The latter 85 forms an important feature of my invention since it is so constructed and arranged as to form not only an integral reinforcement for the burner but also a means for conducting heat from the walls of the combustion chamber K back to the nozzle portion X. As this is a portion of the burner where it is desirable to have a high degree of heat this particular arrangement is of material advantage. I do not however desire to limit the 90 invention to the particular construction shown except as ultimately set forth in the claims.

I claim:

1. In a blow torch or the like, the com- 110

bination with a tank, of a burner therefor, said burner having a longitudinally extending combustion chamber, a discharge nozzle at the rear thereof, said nozzle having its forward extremity projecting into the rear of the combustion chamber, said burner having a bottom portion forming a fuel conducting passage to said nozzle, and a top lug integrally connecting the rear of the 10 combustion chamber at a point intermediate the length of the nozzle and the rear portion of the nozzle, said lug being spaced from said nozzle and extending diametrically opposite the said bottom fuel conducting portion of the burner to form therewith longitudinally extending air ports around a portion of the said forwardly projecting extremities, said lug extending longitudinally of the combustion chamber and being of a 20 reinforcing character to form an integral reinforcement for the burner and also for conducting heat from the walls of the combustion chamber to the nozzle.

2. In a blow torch or the like, the combination with a tank, of a burner therefor, 25 said burner having a longitudinally extending combustion chamber, a discharge nozzle at the rear thereof, said nozzle having its forward extremity projecting into the rear of the combustion chamber, said burner having a bottom portion forming a fuel conducting passage to said nozzle, and a lug integrally connecting the rear of the combustion chamber at a point intermediate the 30 length of the nozzle and the rear portion of the nozzle, said lug being spaced from said nozzle to form air ports with the said bottom fuel conducting portion of the burner, said lug extending longitudinally of the combustion chamber, and being of a reinforcing character to form an integral reinforcement for the burner and also for conducting heat from the walls of the combustion chamber to the nozzle. 35 40

In testimony whereof I affix my signature.
OTTO J. GROEHN.
